HYDRAULIC ELEVATOR TORQUE DAMPER

Edwin C. Rosenberg, Milwaukee, Wis.

Application September 17, 1932, Serial No. 633,567

3 Claims. (Cl. 60—6)

My invention relates to improvements in hydraulic elevator torque damper.

The object of my invention is to provide means whereby a hydraulic elevator operated by a motor driven pump may be stabilized in its operation, may be so constructed as to prevent jarring, and unduly rapid starting and stopping in its upward movements.

More specifically stated, it is the object of my invention to dampen out the starting and stopping acceleration and deceleration of a hydraulic elevator by providing a heavy fly wheel upon the motor shaft, and to so construct that fly wheel that the cutting off of a portion of the flange 15 thereof may be accomplished at the factory upon mathematically figured data, including the weight of the cage and the estimated load requirements to adjust the dampening effect in accordance with the demands of the particular installation.

20 In the drawing:

Figure 1 is a side elevation of a hydraulic elevator structure embodying my invention, a portion of the main cylinder being shown in vertical section.

25 Figure 2 is a vertical section through the fly wheel shown in Figure 1.

Figure 3 is a section showing the fly wheel adjusted for lighter loads.

Like parts are identified by the same reference 30 characters throughout the several views.

In a hydraulic elevator the cage 10, shown in fragmentary view in Figure 1, is mounted upon a ram 11 which operates in a cylinder 12. A piston 13 on the end of the ram 11 is caused to be elevated in the piston 12 by fluid pressure in the space 14 below the piston. Pressure of the fluid at 14 is controlled by means of a pump 15 which passes fluid from a reservoir 16 through pipe 17 and into pipe 18, leading into the 40 cylinder.

Pump 15 is of the gear or vane type, the operating element of which is housed in the main pump structure 15 and is actuated by a shaft 19 coupled to the armature shaft 20 of a motor 21. 45 Structure of the type thus far described is common in the hydraulically operated elevators heretofore known. Each of such elevators is, of course, installed in locations calling for certain maximum and minimum load requirements, 50 and the sizes of the parts used in general correspond to the size of the loads expected to be carried. However, it is obvious that loads carried by elevators will vary from time to time, and in any event, a wide range of load capacity 55 may be expected.

If the load in cage 10 is light the energizing of motor 21, which has a capacity for an exceedingly heavy load in cage 10, causes an exceedingly rapid passage of fluid through the pump 15 and through the pipe 18 into the cylinder so as to rapidly accelerate the movement of the cage 10 in an upward direction. Assuming a heavy load in cage 10, the motor 21 undertakes its burden of forcing the pump 15 to thrust liquid into the chamber 14 beneath the piston slowly and gradually so that the load starts easily and satisfactorily.

However, when the cage approaches a higher level comprising its unloading point, the deenergization of the motor 21 is the signal for instantaneous stoppage of the elevator, since the heavy load and its resistance to further flow of liquid in pipe 18 will induce a considerable back pressure to stop the rotation of shaft 19, and therefore of armature shaft 20.

On the other hand, the light load which was started with unnecessarily rapid acceleration from the lower level approaches the upper level or unloading point at a maximum speed, and the deenergization of motor 21 does not immediately result in stoppage of the elevator since the armature shaft 20 and the shaft 19 of the pump will tend to continue in rotation with the result that the cage 10 may pass the unloading point and necessitate a readjustment by the operator of the controls so as to return the elevator downwardly to its proper unloading point.

To avoid these difficulties I provide upon the end 22 of the armature shaft a fly wheel 25 which comprises a hub 26, a web 27, and an elongated annular flange 28. This fly wheel, situated as it is upon a shaft 22, integral with shaft 20 and secured to the pump through shaft 19, has an "advantage" with reference to the fluid pressures at 14 by reason of the inherent capacity of the pump 15. With a fly wheel 25 of the proper weight adjusted to the capacity of the elevator cage 10, I am able to control the starting of a light load, since the motor 21 must overcome the inertia of fly wheel 25 as well as the inertia and weight of the load in the cage 10.

The inertia of fly wheel 25 must, of course, be overcome when the load in cage 10 is great, but the difficulty in starting a large load in cage 10, even though augmented by the inertia of the fly wheel 25, is not an objectionable feature in the operation of a hydraulic elevator, and when the heavy load in cage 10 approaches the unloading point at a higher level the deenergization of the motor 21 is not a signal for sudden stoppage, since

the fly wheel 25 has the momentum of stored inertia which in being overcome accomplishes work in raising the elevator to the higher level. The heavy load on cage 10 does not, therefore, immediately stop with a jolt.

If the elevator has a light load in cage 10 and the fly wheel with its inertia must be slowly started, it will likewise slowly stop at the higher level without the difference in operating effect which would otherwise be the case if the fly wheel was not there.

The result of operation of the hydraulic elevator with my fly wheel is smooth starting and smooth stopping, something that has been sought in elevators of this type throughout the history of hydraulic elevators.

Obviously, a single fly wheel would not be suitable for all types of installations in conjunction with all sizes of hydraulic elevators. I have found, however, that a single fly wheel may be provided with an elongated annular flange 28, and a portion of the annular flange as delineated in dotted lines at 29 in Figure 2 may be cut away at the factory from a stock wheel. Adjustments may thereby be made for large or small installations by cutting off the excess of flange 25.

I claim:

1. The combination with a hydraulic elevator including a cylinder, a ram, and a positive displacement pump with appropriate direct pipe connections for establishing unyielding liquid pressure in the cylinder, of a shaft for operating the pump, a substantially constant torque motor attached to the pump shaft, and a torque damper comprising a flywheel upon said shaft.

2. The combination with a hydraulic elevator including a positive displacement pump therefor adapted to start and stop in accord with elevator movement, a shaft for the pump, a substantially constant torque motor coupled to said shaft, and a fly wheel for said motor provided with an elongated flange weight adapted to be initially and permanently adjusted in accord with the capacity of the elevator.

3. The combination with a hydraulic elevator and a pump therefor adapted to start and stop in accord with elevator movement, of a motor coupled to the pump whereby to provide a liquid supply to the elevator substantially without pulsation, and a heavy fly-wheel connected to the motor, whereby to damp starting torque and resist deceleration thereof.

EDWIN C. ROSENBERG.
